UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING LOOM.

1,372,315.

Specification of Letters Patent. Patented Mar. 22, 1921.

Application filed April 12, 1918. Serial No. 228,135.

To all whom it may concern:

Be it known that I, EPPA H. RYON, a citizen of the United States, residing at Waltham, in the county of Middlesex and State 5 of Massachusetts, have invented a new and useful Weft-Replenishing Loom, of which the following is a specification.

This invention relates to a weft replenishing loom of the type in which a fresh weft carrier is inserted before complete exhaustion 10 of the active weft carrier.

Such looms are commonly provided with weft detecting mechanism of the so-called feeler type by which the weft carrier transfer 15 is controlled. When a weft carrier is ejected before complete exhaustion a weft thread extends from the ejected carrier to the adjacent selvage of the cloth.

It is the general object of my present invention to provide devices effective to prevent 20 this trailing weft thread or any part thereof from being carried into the cloth by the shuttle as it leaves the shuttle box in which the transfer has occurred.

With this general object in view, an important feature of my invention relates to the provision of a continuously rotated roll disposed substantially beneath the shuttle box when the latter is in forward position, 30 and so rotated that the weft carrier will pass downward at the front of the roll into the usual can or receptacle. Suitable provision is also made for guiding the weft thread to the roll and for preventing slack thread between 35 the roll and the selvage. This provision may include notches cut in the lay to engage the thread and prevent the thread from slipping forward along the slot in the lay toward the selvage as it is pulled downward.

A further feature of my invention consists in the provision of means for straightening the thread as it is drawn through and out of the shuttle box by the roll, so that loops or 45 kinks in the threads may not be caught between the shuttle and the wall of the shuttle box, causing breakage of the thread and leaving a loose end which may be woven into the cloth.

Another important feature of my invention relates to the provision of means for preventing removal of the weft carrier from the receptacle provided therefor through the operation of the roll as it unwinds the remaining weft from the ejected weft carrier.

My invention further relates to arrangements and combinations of parts which will be hereinafter described and more particularly pointed out in the appended claims.

A preferred form of my invention is 60 shown in the drawings, in which—

Figure 1 is a side elevation of a portion of a loom embodying my invention, the lay being shown in section;

Fig. 2 is a plan view of the parts shown in 65 Fig. 1, and

Fig. 3 is a plan view of the roll and its driving mechanism.

Referring to the drawings, I have shown a loom side 10 supporting a multi-color magazine frame 11 on which is mounted a trans- 70 ferrer 12 of the usual type. The magazine and transerrer form no part of my invention and are shown only in fragmentary form.

The lay 13 is supported in the usual way by swords 14 pivoted to a rock shaft not shown, and the forward portion of the lay is cut away below the shuttle box to provide clearance for a roll 15 fixed to a shaft 16 80 (Fig. 3) rotatable in a bearing 17 in the end of an arm 18 pivotally mounted on a stud 19 fixed in a bracket 20 secured to the loom side 10. A stop 21 (Fig. 1) on the bracket 20 limits the movement of the arm and roll 85 toward the lay, and a spring 22 disposed between the stop 21 and a lug 23 on the arm 18 normally holds the roll in the position shown in Fig. 1. This yielding support permits the roll to swing forward if any obstacle 90 finds lodgment between the roll and the lay.

A grooved collar or pulley 24 (Fig. 3) is fixed to the shaft 16 and is connected by a cord or belt 25 to a double-grooved collar 26 95 loosely rotatable upon the stud 19. A second cord or belt 27 connects the collar 26 to the crank shaft or to some other suitable rotating member, and through these connections the roll 15 is continuously rotated in 100 the direction of the arrow *a* (Fig. 1) while the loom is in operation. The plate 30 forming the bottom of the shuttle box is provided with a plurality of notches 31, as indicated in Fig. 2, and for a purpose to be de- 105 scribed.

The usual weft carrier receptacle 32 (Fig. 1) is provided with a removable cover comprising downwardly inclined plates 33 and 34 which prevent removal of a weft carrier 110

from the receptacle while the cover is in position. The plate 34 is provided with deep notches 35 through which the weft thread may be drawn by the roll 15 while the intervening teeth engage and prevent exit of the weft carrier.

The successful operation of the mechanism necessitates the prompt severing of the weft thread at a point closely adjacent the 10 selavage, and for this purpose I provide a thread cutter 36 of the type shown in my prior Patent No. 939,445, issued to me November 9, 1909. My cutter 36 coöperates with blades 37 mounted on the temple 38 and is operated at each weft carrier transfer through a rod 39 (Fig. 1). This rod 39 corresponds to the rod 32 in my prior patent 15 and is controlled and actuated by similar mechanism.

The operation of the mechanism thus far described is as follows: When a substantially exhausted weft carrier C is ejected from the shuttle, it passes downward past the roll 15 and the baffle plates 33 and 34 to 25 the position indicated at C' in Fig. 1. The weft thread W assumes the position shown in full lines in Figs. 1 and 2 and is promptly severed by the thread cutter 36. As the lay moves back the thread W engages the roll 30 15 which is preferably covered with felt or other similar fabric, and the weft end extending to the thread cutter is drawn quickly downward. The notches 31 prevent the weft thread from slipping along the slot in 35 the bottom of the shuttle box toward the thread cutter, and thus prevent the occurrence of slack thread which might be carried into the cloth.

As soon as the thread is cut, however, 40 it has a tendency to snarl or kink as indicated at 40 in Fig. 2. In order to prevent such snarls or kinks from being caught between the binder or box plate and the side of the shuttle, I provide soft wool or bristles 45 41 secured to the binder 42 and engaging the side of the shuttle adjacent its inner end. As the weft thread W is drawn past this wool or bristles, the snarls are easily removed therefrom, thus preventing catching and breaking of the thread as it is 50 drawn from the shuttle box.

While the severed end of the weft thread is being drawn downward by the roll 15 the thread extending to the weft carrier is 55 being drawn rapidly upward and is being wound about the roll 15. Such rapid unwinding of the weft from the weft carrier would frequently cause the weft carrier to be jerked from the receptacle if it were not 60 for the baffle plates 33 and 34. The position of the weft after it has been caught by the roll 15 is indicated at W' in dotted lines in Fig. 1.

The roll 15 is provided with a groove 15* 65 through which a knife may be passed to re-

move the weft thread therefrom at suitable intervals.

It will appear, therefore, that I have provided simple and reliable means for quickly removing the severed weft end from the shuttle box and also for removing the waste yarn from the ejected weft carrier, both of which results are highly desirable.

Having thus described my invention it will be evident that changes and modifications can be made therein by those skilled in the art without departing from the spirit and scope thereof as set forth in the claims, and I do not wish to be otherwise limited to the details herein disclosed, but what I so claim is:—

1. A weft replenishing loom having, in combination, a lay, a shuttle, means to eject a substantially exhausted weft carrier from said shuttle, a receptacle for the ejected weft carriers, a weft-engaging roll supported by the loom frame and adjacent the lay when the latter is in its forward position, and means to rotate said roll in a direction to advance ejected weft carriers toward said receptacle and to pull downward the trailing weft end. 85 90

2. A weft replenishing loom having, in combination, a lay, a shuttle, means to eject a substantially exhausted weft carrier from 95 said shuttle, a weft-engaging roll mounted on the loom and adjacent the lay when the latter is in its forward position, means to rotate said roll, and a yielding support for said roll, whereby said roll is permitted to 100 swing forwardly out of normal position, when the normal positions of the lay or the roll are obstructed.

3. A weft replenishing loom having, in combination, a lay, a shuttle, means to eject 105 a substantially exhausted weft carrier from said shuttle, a roll mounted on the loom frame and adjacent the lay when the latter is in its forward position, means to rotate said roll in a direction to draw the thread 110 downward out of the shuttle, a thread cutter, and thread guiding devices on the lay adapted to guide the severed thread from the cutter to the roll.

4. A weft replenishing loom having, in 115 combination, a lay, a shuttle, means to eject a substantially exhausted weft carrier from said shuttle, a receptacle for the ejected weft carriers, a roll mounted on the loom and adjacent the lay when the latter is in 120 its forward position, means to continuously rotate said roll, said roll being effective to engage the trailing weft end and to unwind the remaining weft from an ejected weft carrier, and means carried by said receptacle 125 effective to prevent removal of said weft carrier from said receptacle by said roll while unwinding the weft therefrom.

5. A weft replenishing loom having, in combination, a lay, a shuttle, means to eject 130

- a substantially exhausted weft carrier from said shuttle, a receptacle for the ejected weft carriers, a roll mounted on the loom and adjacent the lay when the latter is in its forward position, means to continuously rotate said roll, said roll being effective to engage the weft end connected to an ejected weft carrier and to unwind the remaining weft from said weft carrier, and means to prevent removal of said weft carrier thereby from said receptacle, said means comprising coacting baffle plates forming a cover for said receptacle and one of said plates having thread guiding notches therein.
6. A weft replenishing loom having, in combination, a lay, a shuttle, means to eject a substantially exhausted weft carrier from said shuttle, a roll mounted on the loom and adjacent the lay when the latter is in its forward position, means to rotate said roll, in such a direction that it will engage and draw downward the severed weft end, and means to straighten said weft end as it is drawn downward by said roll.
7. A weft replenishing loom having, in combination, a lay, a shuttle, means to eject a substantially exhausted weft carrier from said shuttle, a weft-engaging roll mounted

on the loom and adjacent the lay when the latter is in its forward position, means to continuously rotate said roll, to draw the trailing weft end downward, and weft straightening devices mounted on the side of the shuttle box and adjacent the mouth thereof, adapted to engage and straighten the severed weft thread as it is drawn into said box and downward therefrom by said roll.

8. A weft replenishing loom having, in combination, a lay, a shuttle, means to eject a substantially exhausted weft carrier from said shuttle, a weft-engaging roll mounted on the loom and adjacent the lay when the latter is in its forward position, means to continuously rotate said roll, a shuttle binder and weft straightening devices comprising flexible fibers secured to the end of said shuttle binder, and engaging and pressing the trailing weft end against the side of the boxed shuttle, thereby straightening said weft end, as it is drawn downward by said roll.

In testimony whereof I have hereunto affixed my signature.

EPPA H. RYON.
